REFRIGERATOR CABINET

Filed Feb. 6, 1931

INVENTOR
FRANK C. BURTON.

BY *Le Roy Williams*
ATTORNEY

UNITED STATES PATENT OFFICE

FRANK C. BURTON, OF EVANSTON, ILLINOIS, ASSIGNOR TO MAJESTIC HOUSEHOLD UTILITIES CORPORATION, OF CHICAGO, ILLINOIS, A CORPORATION OF ILLINOIS

DESIGN FOR A REFRIGERATOR CABINET

Application filed February 6, 1931. Serial No. 38,568. Term of patent 14 years.

To all whom it may concern:

Be it known that FRANK C. BURTON, a citizen of the United States of America, residing at 1008 Brummel Street, Evanston, Illinois, in the county of Cook and State of Illinois, has invented a new, original, and ornamental Design for Refrigerator Cabinets, of which the following is a specification,

reference being had to the accompanying drawing, forming part thereof.

The figure is a perspective view of a refrigerator cabinet, showing my new design.

I claim:

The ornamental design for a refrigerator cabinet as shown.

FRANK C. BURTON.
